DOOR SILENCER

Harry N. Holm, Minneapolis, Minn.

Application July 27, 1946, Serial No. 686,647

1 Claim. (Cl. 292—79)

1
This invention relates to door silencers adapted to assure proper and quiet closing of a hinged door when the same is initially swung towards closed position or even forcibly slammed.

It is an object of my invention to provide comparatively simple but highly efficient apparatus for checking the forceful closing or slamming of a hinged door; for substantially eliminating noise during the closing action and for positively engaging and properly closing the door after it has been checked and swung beyond a predetermined position.

More specifically, it is an object to provide closely cooperating mechanism which first causes the free edge of a door, during its swinging towards closed position, to be yieldably engaged, arrested in slamming movement and thereafter, positively and fully closed, through spring power reacting against a yieldable checking mechanism.

Another object is to provide door silencing and retaining mechanism by the use of which a door may be forcibly and freely swung throughout the greater part of its closing cycle from fully opened position and whereby in the last portion of its closing operation, regardless of swinging violence, it is silently restricted and immediately thereafter, forcibly but quietly closed and retained in closed position.

These and other objects and advantages of my invention will be more apparent from the following description made in connection with the accompanying drawings, wherein like reference characters refer to similar parts throughout the several views and in which:

Fig. 1 is an upper perspective view showing an embodiment of my apparatus operatively mounted upon the door frame of a vertically hinged door with the door being shown in partially closed position, just prior to engagement of the free marginal portion thereof with the striker member of my door-engaging and closing mechanism.

Fig. 2 is a somewhat diagrammatical view mostly in top plan, on a smaller scale, showing the essential mechanism of my apparatus during initial and subsequent operation thereof.

Fig. 3 is a side elevation showing a preferred form of door-engaging and closing mechanism in its door-receiving position effected through normal opening of the door from closed position.

Fig. 4 is a vertical section taken longitudinally through my cooperating, door-checking mechanism.

Fig. 5 is a top plan view showing my apparatus as it is positioned when the door is fully closed.

2

Fig. 6 is a fragmentary, rear elevation of the back of the free corner of the door showing a noiseless striker pad mounted thereon; and

Fig. 7 is a cross-section taken on the line 7—7 of Fig. 6.

As shown in the drawings, an embodiment of my apparatus is applied to a door and doorway of conventional type, most of my apparatus being mounted upon the outer facing and beam of the doorframe DF.

My apparatus includes a spring-actuated door-engaging and closing mechanism which conveniently can be mounted at the upper portion of the door frame facing and which, as shown, is provided with a horizontally bifurcated bracket 10 having a vertical attachment flange 10a fixed to the doorway facing and having upper and lower outwardly and horizontally extending, parallel arms 10b and 10c, respectively. Between the outer ends of arms 10b and 10c, a door-engaging and closing lever in the form of a more or less arcuate plate is pivotally mounted, as shown, being fulcrumed below and to the upper supporting arm 10b by means of a large diameter rivet 12, a bearing collar 12a being fixed to the medial portion of lever 11 for effecting the free swinging of this mechanism. Near the outer end of lever 11 and at opposite sides thereof, axially aligned, vertical spring attachment posts 13 are provided, each being connected near its outer extremity with a horizontally extending contractile spring 14, said springs being disposed in parallel horizontal relationship and being anchored at their inner ends to bracket 10 by means of vertically aligned anchoring posts 15, one of which is secured to the upper arm 10b of the bracket and the other of which is secured to the lower arm 10c of the bracket. The springs 14 are as nearly as possible, identical in construction, length and tension so that the inward pull upon posts 13 above and below lever plate 11 is equalized.

Lever 11 at its inner end carries a cushioning striker disc 16 which is constructed from somewhat compressible and non-resonant material such as vulcanized rubber and this disc is positioned, as shown in Fig. 2, to be disposed with only a portion of its periphery (preferably less than 180 degrees) in the path of the free edge of the door during a fragment of the closing movement of the door, which precedes slightly, swinging of the door into opposition to the door jamb. The relationship of the fulcrum 12 for lever plate 11 and the connections of contractile springs 14 is such that a dead center

positioning is obtained as clearly shown in Fig. 2, when the lever is disposed in substantially its extreme outermost position with striker disc 16 positioned as described for engaging the free end of the door. At the outer end of the lever 11, a door-retaining and closing roller 17 is pivotally mounted on a vertical axis, preferably being provided with an axial sleeve bearing 17a which is journaled on a depending pivot post 18 fixed to the outer end of the lever. The roller 17 is constructed from a suitable non-resonant, somewhat compressible material such as vulcanized gum rubber. This roller preferably does not engage directly against the outer surface of the door but to effect proper and positive closing and silencing of the door, rolls upon a bent or inclined camming plate 19 which is adjustably secured to the upper portion of the outer surface of the door, having as shown, an attachment foot 19a which may be rigidly connected with the door by screws or other means. The plate 19 preferably is made of relatively rigid but bendable sheet metal having some degree of resiliency but capable of retaining its shape when bent by force to a predetermined angular position with reference to the vertical outer surface of the door. Adjustment of this camming plate 19 may be made first by its point of attachment on the door and secondly, by varying the angulation or bending, as has been described.

The mechanism previously described comprises an important cooperating part of my mechanism but will not, of itself, produce the highly important and desired combinative results of silencing or checking the door during the final closing thereof.

Cooperatively associated with my door-engaging and closing mechanism is a cushioning and checking mechanism mounted as shown, from the upper beam of the doorway and disposed behind the doorstop S. This mechanism, as shown, comprises a horizontal dashpot cylinder 20 having its axis disposed substantially parallel with the door jamb and having slidably mounted therein, a piston 21 provided with a sealing ring or pump washer 21a for sealing engagement with the interior of the cylinder. Piston 21 is urged to protracted or outward position by a light spiral spring 22 interposed between the rear end 20a of cylinder 20 and the rear of the sealing washer 21a. Cylinder 20, at its forward end is provided with a relatively large air escape port 20b and at its rear end is provided, as shown, with an axially disposed ball-accommodating valve port 20c terminating at its outer end in the restricted air intake passage. A ball 20e is loosely accommodated in passage 20c and is retained in the passage by slightly swedging the inner edge of the passage. An outwardly tapered, restricted air discharge port or by-pass 20f is formed through the rear end 20a of the cylinder effective to restrict the discharge of air from behind the piston and so check the closing action of the door when the piston is forced inwardly or rearwardly within cylinder 20.

Piston 21 has attached to the forward face thereof, an axially and horizontally extending thrust transmitting rod 23 which is mounted in a relatively thick slide bearing 20d provided by the forward end of the cylinder. In the fully extended position of rod 23, the end of the rod is disposed a short distance, say from one and one half to two and one half inches, outwardly and forwardly of the door jamb and in position to be abutted by an abutment member 24 mount-

ed on the inner vertical face of the door immediately after the free edge of the door has engaged striker disc 16 and tripped the lever 11 beyond dead center position. The door-carried abutment member 24 may comprise any suitable compressible member and, as shown, is in the form of a rubber disc 24a housed and mounted in a flared annular collar 24b which has an attachment flange secured to the inner face of the door.

Operation

In operation, the opening of the door D, through riding engagement of the retaining roller 17 upon camming plate 19 swings the lever to the extended dead center position shown in Figs. 1 and 2, the tension springs 14 holding the lever plate in such dead center or projected position. In this connection a depending stop lug 10d may be provided at the outer end of plate 10b of the bracket. Simultaneously with the opening of the door, the piston rod 23 is protracted to the full line position shown in Figs. 1 and 2.

To close the door, it is only necessary to forcibly swing the same towards closed position and regardless of the amount of force used, slamming and production of any appreciable noise is prevented through the combinative effect of my apparatus.

The door, as it approaches closed position, first engages the compressible striker disc 16 at its marginal edge, momentarily checking the violence of the door swinging and instantaneously tripping lever 11 and simultaneously engaging the thrust-applying piston rod 23 with the cushioning abutment 24a on the door. The door is then forced into closed position by the power of the two tension springs 14, the roller 17 being disposed outwardly of the free edge of the door and in camming engagement through roller action with the cam plate 19. In the controlled closing of the door, the power of the springs 14 is resisted by the dash pot mechanism to the end that the door is moved slowly but positively into abutment with the door stop S, being at its free portion, interposed with no play possible, between the closing roller 17 and the thrust-applying plunger rod 23. Violent impact or shock is quickly and almost noiselessly cushioned by the initial striking of the free edge of the door against the striker disc 16 with the almost simultaneous air cushioning of the impact through abutment of the thrust-applying rod 23 with the compressible abutment member 24a mounted on the inner face of the door.

In the operation of my apparatus, the swinging of the door-engaging and closing lever 11 is smooth, silent and uniform due to its mounting and to the uniform application of the spring power applied to points spaced from both upper and lower sides of the lever plate 11. With this improved construction, simplification of parts is effected and a high efficiency is obtained with a lever pivoted to only one of a pair of arms and constructed from a single rather than a double spaced plate of material.

The cooperation of the closing roller 17 with the inclined or angled camming plate 19 is of high importance since it progressively, through constant rolling action applies closing force to the free end of the door. With the plate 19 properly adjusted there is no impact, blow or force upon the tripping of lever 11 or any subsequent snapping due to the rolling action and the proper angulation of the camming plate relative to the

positioning of the plunger of the dash pot and the relative positioning of the striker disc 16.

From the foregoing description, it will be seen that I have provided a simplified and highly efficient apparatus for checking the forceful closing or slamming of a hinge door and substantially eliminating noise during the entire closing operation as well as for positively closing the door after it has been swung to a predetermined position in relation to the door jamb.

It will, of course, be understood that various changes may be made in the form, details, arrangement and proportions without departing from the scope of my invention.

What I claim is:

In apparatus for completing the closing of a hinged door, a bifurcated supporting bracket mounted on a door-way adjacent the jamb having a pair of outwardly extending, spaced horizontal arms, a substantially arcuate lever in the form of a heavy flat plate intermediately pivoted in said bracket between the outer ends of said arms for swinging movement on a vertical axis, a striker element mounted on the inner end of said lever plate and partially disposed in the line of travel of the free edge of the door during the near-closing movement thereof, a pair of horizontally extending, parallel, tensioned coil springs anchored at their inner ends to the arms of said bracket at vertically aligned points disposed inwardly of the fulcrum of said lever and having their outer ends connected with said lever plate at vertically aligned points disposed outwardly of the fulcrum of said lever and adapted to normally hold said lever in outwardly projecting, over-dead center position when the door is opened and in inwardly swung over-dead center position when the door is closed, said two springs stabilizing strains during operation of the mechanism at

opposite sides of said lever plate during operation, a door-engaging and door-closing roller pivotally connected with the outer end of said lever for rotation on a vertical axis and positioned beyond the path of said door in closing and adapted to be disposed in overlapped relation with the outside of said door when said lever is tripped from one side of dead center position whereby said springs act to cause said lever to close the door, and a roller-engaging rider plate attached to the outer surface of the door adjacent the free edge thereof and extending in inclined relation to the outer surface of the door from the free edge of the door inwardly thereof for engaging said roller and causing riding action of said roller thereon to prevent snap action and noise in the operation of the device, said rider plate having a free end adjacent the free edge of the door and an attachment end disposed inwardly thereof and being constructed from material which may be bent with force applied to adjust the inclined angulation thereof with respect to the outer surface of the door.
